(57) **CLAIM**

The ornamental design for a USB memory device, as shown and described.

DESCRIPTION

FIG. 1 is a left side view of the USB memory device.

FIG. 2 is a front view of the USB memory device.

FIG. 3 is a right side view of the USB memory device.

FIG. 4 is a rear view of the USB memory device.

FIG. 5 is a top view of the USB memory device, the bottom being the same.

FIG. 6 is a rear right perspective view of the USB memory device.

FIG. 7 is a rear right perspective view of the USB memory device with the secondary USB connector extended.

FIG. 8 is a front left perspective view of the USB memory device; and,

FIG. 9 is a front left perspective view of the USB memory device with the primary USB connector extended.
